CARRIER BAGS

Harry Frederick Gatward, East Grinstead, England
Application February 16, 1956, Serial No. 566,029
Claims priority, application Great Britain
September 21, 1955
5 Claims. (Cl. 229—54)

This invention relates to carrier bags of the kind which are composed of paper and which are stiffened along each edge adjacent the mouth usually by means of a cardboard or like stiffening member, the stiffened edges being in the form of flaps which can be folded inwardly in opposite directions so that the carrier bag assumes virtually the form of a box.

The chief object of the invention is to evolve an improved form of carrier bag of the box-type incorporating a simple form of fastening means for maintaining the bag in a closed condition.

A box-type carrier bag in accordance with the present invention is provided along its upper edge with two cardboard or other stiffening flaps which are capable of inward hinging movement in opposite directions so that they occupy a superimposed position, the lower flap carrying one or more string or other type handles adapted to be passed through a slot or slots in the upper flap so as to thereby secure the flaps in superimposed relationship and the bag in its closed condition.

The two flaps project upwardly from the mouth of the bag on its opposite sides, in which case the bag may be provided with subsidiary flaps at the ends of the mouth, which subsidiary flaps are turned inwardly beneath the main flaps to provide a complete closure. It is preferred, however, that the two subsidiary flaps and the main flaps shall be so joined together that they form an upward extension of the bag's mouth, the upward extension being foldable along suitably positioned crease lines so as to completely close the mouth of the bag.

According to a further feature of the invention, each slot in the upper flap includes a central comparatively wide part through which the handle can be easily passed, the slot converging along its edges towards its ends, the edges of the material adjacent the narrower parts of the slot frictionally gripping the handle and preventing any tendency for the upper flap to ride up the handle into an open position, the weight of the bag and its contents when carried tending to force the string or like handle into the narrower end parts of the slot.

A further object of the invention is to provide improved means associated with such a carrier bag which will enable a garment or the like to be supported therein, the carrier bag with this object in view having associated with it a garment hanger which may be detachable or alternatively may form a integral part of the bag.

Referring to the drawings:

Figure 1 is a perspective view showing how the carrier bag can be folded to occupy a small space;

Figure 2 illustrates the carrier bag open;

Figures 3 and 4 illustrate how the flaps are folded over to close the mouth of the bag;

Figures 5 and 6 illustrate the bag in its closed condition;

Figure 7 is a fragmentary perspective view looking 70 in the direction of the arrow "A" in Figure 2;

Figure 8 is a section on the line 8—8 in Figure 6;

2

Figures 9 and 10 are perspective views of a carrier bag incorporating an integral garment hanger;

Figure 11 illustrates the garment hanger in use; and

Figure 12 is a perspective view illustrating how a garment hanger of special form can be mounted in the bag.

As will be seen clearly from the accompanying drawings which illustrate a preferred form of box-like carrier bag in accordance with the invention, the bag is capable of being folded into a flat condition as is shown clearly in Figure 1, the bag when extended ready to receive the articles to be carried having the form shown in Figure 2.

The bag 1 at the mouth carries two cardboard or other internally arranged stiffeners 2 and 3, stiffener 2 which is to form the lower of the two main flaps, being of rectangular form and extending across the full width of the bag's mouth. Stiffener 3, on the other hand, has its upper corners cut off at 45° as at 4 to facilitate folding.

Flap 2 carries one or more string or like handles 5 (two being shown although one handle may be sufficient in the case of a comparatively narrow bag). Handles 5 are integrally formed as a closed string or cord loop, and are passed through holes 6 in flap 2 so that they project upwardly therefrom in spaced relationship.

Flap 3 is formed with two spaced slots 7 which are comparatively wide at the centre to permit easy entry of the handles, each slot tapering towards its ends, which latter terminates in holes 8. The purpose of this particular form of slot will be described later.

Assuming that the articles have been placed in the bag, flap 2 is first folded inwardly into the position shown in Figure 3. The end flaps 9 are then folded inwardly into the position shown in Figure 4 and the handles passed through slots 7, flap 3 being then folded

inwardly and downwardly into the position shown in Figure 5. Tension is then applied to the handles to cause them to register with holes 8, the holes 8 being of a diameter such that the material bordering the holes will grip the handles and prevent the flap riding up the handles and lifting from its closed position, this being assisted by the narrow formation of the slots near their ends.

It will be appreciated that in this position the bag will be completely closed and the contents fully protected.

To facilitate folding the bag, it is formed with suitably positioned crease lines.

The bag may, as is shown clearly in Figures 9, 10, and 11, be provided with an intergral garment hanger, the latter in its simplest form, consisting of a strip 10 of cardboard or other comparatively stiff material stapled or otherwise secured to the underside of flap 2, strip 10 being capable of folding along line 11 into a position in which it depends downwardly from flap 2 at right angles.

The strip 10 is cut as at 12 to form a longitudinally arranged slot through which a garment or the like can be passed, so that it hangs therefrom in a neat condition. The cut 12 may be continuous so that the material forming the centre of the depending part of the strip will remove to form the slot or it may be non-continuous as shown, thereby providing a flap 13 which can be bent downwardly to form as shown in Figure 11 a comparatively stiff bar on which the garment G or the like is hung.

As a further alternative, as is shown clearly in Figure 12, a wire garment hanger 24 of special construction may be provided, the latter being fitted with an arm 15, the limbs of which are passed through the loops of the handles so that the hanger will be supported within the carrier bag. Such an arrangement has the advantage that a garment can be first placed on the hanger and the hanger plus garment then inserted in the bag. The hanger

together with the garment can afterwards be removed from the bag and suspended in a wardrobe by the hook 16.

For convenience in manufacture, both flaps 2 and 3 may be formed with identical slots which may be formed in one operation, the unwanted parts of the slots in the flap 2 being covered by a piece of paper or the like 14 as shown in Figure 3. Alternatively, the flap 2 may be formed merely with four suitably spaced holes through which the string forming the handles is threaded.

I claim:

1. A collapsible carrier or container comprising an open top bag formed of relatively thin flexible sheet material and of rectangular transverse section when open for use and foldable flat for storage, a pair of relatively stiff sheets secured across the opposed wider sides of said bag at the tops thereof, said sheets having a length substantially equal to the width of said wider bag sides and a width substantially equal to the width of the narrower sides of the bag, said sheets and bag portions secured thereto being foldable inwardly into superimposed relation transversely of said bag to retain the bag in open rectangular condition, one of said sheets and bag portions secured thereto being the upper of said sheets when in superimposed relation and having a slot extending longitudinally of said sheet, and a flexible handle having its ends anchored to the other of said sheets substantially in registration with the ends of said slot when said sheets are folded into superimposition and adapted to be inserted through said slot to retain said sheets and bag portions in folded superimposed relation closing the bag in a watertight manner and evenly supporting all sides of the bag.

2. A collapsible carrier or container comprising an open top bag formed of relatively thin flexible sheet material and of rectangular transverse section when open for use with substantially even top edges and inward folds for use with substantially even top edges and inward folds longitudinally of the narrower sides to enable folding flat for storage, a pair of relatively stiff sheets secured across the opposed wider sides of said bag at the tops thereof, said sheets having a length substantially equal to the width of said wider bag sides and a width substantially equal to the width of said narrower bag sides, one of said sheets being rectangular and substantially corresponding to the transverse section of said bag, the other of said sheets having beveled corners adjacent the top edges of the bag with the bevels extending from the corners spaced from said top bag edges to the top edge of said sheet, said sheets and bag portions secured thereto being foldable inwardly into superimposed relation transversely of said bag to retain the bag in open rectangular condition with the beveled sheet overlying the rectangular sheet and the side portions and free corners of the bag adjacent the beveled sheet folded inwardly under the beveled sheet, said beveled sheet and bag portion secured thereto having a slot extending longitudinally of said sheet, and a flexible handle having its respective ends anchored to said rectangular sheet substantially in registration with the ends of said slot when said sheets are folded into superimposition and adapted to be inserted through said slot to retain said sheets and bag portions in folded superimposed relation closing the bag in a watertight manner and evenly supporting all sides of the bag.

3. A collapsible carrier or container comprising an open top paper bag of rectangular transverse section when open for use with substantially even top edges and inward folds longitudinally of the narrower sides to enable folding flat for storage, a pair of relatively stiff cardboard sheets secured across the inner surfaces of the opposed wider sides of said bag at the tops thereof, said sheets having a length substantially equal to the width of said wider bag sides and a width substantially equal to the width of the narrower sides of the bag, one of said sheets being rectangular and substantially corresponding to the transverse section of said bag, the other of said sheets having beveled corners adjacent the top edges of the bag with the bevels extending from the corners spaced from said top bag edges to the top edge of said

ing beveled corners adjacent the top edges of the bag with the bevels extending from the corners spaced from said top bag edges to the top edge of said sheet, said sheets and bag portions secured thereto being foldable inwardly into superimposed relation transversely of said bag to retain the bag in open rectangular condition with the beveled sheet overlying the rectangular sheet and the side portions and free corners of the bag adjacent the beveled sheet folded inwardly under the beveled sheet, said beveled sheet and bag portion secured thereto having a slot extending longitudinally of said sheet, and a string handle having its respective ends anchored to said rectangular sheet substantially in registration with the ends of said slot when said sheets are folded into superimposition and adapted to be inserted through said slot to retain said sheets in folded superimposed relation closing the bag in a watertight manner and evenly supporting all sides of the bag, said slot terminating in holes substantially corresponding to the section of said handle with narrow portions adjacent said latter holes to snugly surround said handle and wide portions intermediate said narrow portions to facilitate insertion of said handle through said slot.

4. A collapsible carrier or container comprising an open top paper bag of rectangular transverse section when open for use with substantially even top edges and inward folds longitudinally of the narrower sides to enable folding flat for storage, a pair of relatively stiff cardboard sheets secured across the inner surfaces of the opposed wider sides of said bag at the tops thereof, said sheets having a length substantially equal to the width of said wider bag sides and a width substantially equal to the width of the narrower sides of the bag, one of said sheets being rectangular and substantially corresponding to the transverse section of said bag, the other of said sheets having beveled corners adjacent the top edges of the bag with the bevels extending from the corners spaced from said top bag edges to the top edge of said sheet, said sheets and bag portions secured thereto being foldable inwardly into superimposed relation transversely of said bag to retain the bag in open rectangular condition with the beveled sheet overlying the rectangular sheet and the side portions and free corners of the bag adjacent the beveled sheet folded inwardly under the beveled sheet, said beveled sheet and bag portion secured thereto having a pair of spaced parallel slots extending longitudinally of said sheet, said rectangular sheet having holes substantially registering with the ends of said slots when said sheets are folded into superimposition, and a pair of flexible string handles having their respective ends threaded through said holes and anchored to the inner side of said rectangular sheet and adapted to be inserted through said slots to retain said sheets in folded superimposed relation closing the bag in a watertight manner and evenly supporting all sides of the bag, said slots terminating in holes substantially corresponding to the section of said handles with narrow portions adjacent said latter holes to snugly surround said handles with wide portions intermediate said narrow portions to facilitate insertion of said handles through said slots.

5. A collapsible carrier or container comprising an open top paper bag of rectangular transverse section with substantially even top edges and inward folds longitudinally of the narrower sides, a pair of relatively stiff cardboard sheets secured across the inner surfaces of the opposed wider sides of said bag at the tops thereof, said sheets having a length substantially equal to the width of said wider bag sides and a width substantially equal to the width of the narrower sides of the bag, one of said sheets being rectangular and substantially corresponding to the transverse section of said bag, the other of said sheets having beveled corners adjacent the top edges of the bag with the bevels extending from the corners spaced from said top bag edges to the top edge of said

sheet, said sheets and bag portions secured thereto being foldable inwardly into superimposed relation transversely of said bag with the beveled sheet overlying the rectangular sheet and the side portions and free corners of the bag adjacent the beveled sheet folded inwardly under 5 the beveled sheet, said beveled sheet and bag portion secured thereto having a pair of spaced parallel slots extending longitudinally of said sheet, said rectangular sheet having holes substantially registering with the ends of said slots when said sheets are folded into super- 10 imposition, and a pair of flexible string handles having their respective ends threaded through said holes and anchored to the inner side of said rectangular sheet and adapted to be inserted through said slots to retain said sheets in folded superimposed relation and closing the 15 bag, said slots terminating in holes substantially corresponding to the section of said handles with narrow portions adjacent said latter holes to snugly surround said handles with wide portions intermediate said narrow portions to facilitate insertion of said handles through 20 said slots, and a third relatively stiff cardboard sheet re-

inforcing said rectangular sheet, said third sheet being bent longitudinally into an angle formation with one flange secured to the inner side of said rectangular sheet and the other flange having a longitudinal slot turned at the ends toward the free edge of said flange with a fold line extending between the ends of said slot and defining a flap foldable from said flange to provide a wide slot and an angle bar forming a hanger bar.
